United States Patent Office

Des. 229,820

Patented Jan. 8, 1974

229,820

FIREPLACE GRATE

Richard W. Mellow, Jr., Ladue, Mo., assignor to
Liberty Foundry Co., St. Louis, Mo.

Filed Mar. 16, 1972, Ser. No. 335,462

Term of patent 14 years

Int. Cl. D7—08

U.S. Cl. D7—207

FIG. 1.

FIG. 2.

FIG. 3.

FIG. 4.

FIG. 1 is a front perspective view of a fireplace grate showing my new design;

FIG. 2 is a top plan view of the fireplace grate;

FIG. 3 is a rear elevational view of the fireplace grate; and

FIG. 4 is a right side elevational view of the fireplace grate, the left side being a mirror image thereof.

I claim:

The ornamental design for a fireplace grate, as shown and described.
